(57) **CLAIM**

I claim the ornamental design of a strut assembly, as shown
and described.

DESCRIPTION

FIG. 1 is a front, left, top perspective view of a strut assembly;
FIG. 2 is a front, left, bottom perspective view of the strut assembly of FIG. 1;
FIG. 3 is a rear, right, top perspective view of the strut assembly of FIG. 1;
FIG. 4 is a rear, right, bottom perspective view of the strut assembly of FIG. 1;
FIG. 5 is front elevated view of the strut assembly of FIG. 1;
FIG. 6 is a rear elevated view of the strut assembly of FIG. 1;
FIG. 7 is a left side elevated view of the strut assembly of FIG. 1;
FIG. 8 is a right side elevated view of the strut assembly of FIG. 1;
FIG. 9 is a top plan view of the strut assembly of FIG. 1;
FIG. 10 is a bottom plan view of the strut assembly of FIG. 1;
FIG. 11 is a front, left, top perspective view of the strut assembly of FIG. 1.
FIG. 12 is a front, left, top perspective view of the left strut of the strut assembly of FIG. 1;
FIG. 13 is a front, right, top perspective view of the left strut of FIG. 1;
FIG. 14 is a front elevated view of the left strut of the strut assembly of FIG. 1;
FIG. 15 is a rear elevated view of the left strut of the strut assembly of FIG. 1;
FIG. 16 is a left-side elevated view of the left strut of the strut assembly of FIG. 1;
FIG. 17 is a right-side elevated view of the left strut of the strut assembly of FIG. 1;
FIG. 18 is a top plan view of the left strut of the strut assembly of FIG. 1; and,
FIG. 19 is a bottom plan view of the left strut of the strut assembly of FIG. 1.
The broken lines consisting of dashes show an environment
that forms no part of the claimed design. It will be under-
(Continued)

stood that the right strut of the strut assembly of FIGS. 1-11 is a mirror image of the left strut shown in FIGS. 12-19.
